United States Patent Office.

GEORGE CROMPTON, OF WORCESTER, MASSACHUSETTS.

Letters Patent No. 72,457, dated December 24, 1867.

IMPROVEMENT IN SHUTTLES.

The Schedule referred to in these Letters Patent and making part of the same.

TO ALL WHOM IT MAY CONCERN:

Be it known that I, GEORGE CROMPTON, of Worcester, in the county of Worcester, and State of Massachusetts, have invented certain new and useful Improvements in Loom-Shuttles; and I do hereby declare that the following, taken in connection with the drawings which accompany and form part of this specification, is a description of my invention, sufficient to enable those skilled in the art to practise it.

The invention relates to mechanism for keeping the bobbin from sliding endwise when the spindle is thrown down into the shuttle, and to mechanism for holding the spindle in position both within the shuttle and when thrown up therefrom.

The drawings are illustrations of a shuttle embodying my improvements.

A shows a longitudinal central section of the shuttle; B, a plan of one end of the same; C, a cross-section on the line *z z*.

a denotes the common form of shuttle-shell, having the cavity *b* for receiving the bobbin *c*, which is supported and turns freely on the spindle *d*, the head of said spindle being mounted on a hinge-pin, *e*, so that it may be thrown from its central or axial position within the shuttle up to an angle therefrom, (as seen by the red lines at A,) to enable the empty bobbin to be removed and replaced by a full one.

The part of my invention which relates to retaining the spindle *d* in each of these positions at proper times, consists in fixing in the upper surface of the shuttle a stiff plate-spring, fastened at or near one end to the shuttle-block, and projecting at its opposite end towards the shuttle-cavity, its free or spring end having a recess or concave bed in its under surface, between which and a concave recess or bed in the head of the spindle, a movable block or strut is interposed. This strut being in such position, (relatively to its respective bearings in the spindle-head, and in the spring, and to the pin on which the spindle turns,) that when the spindle is within the shuttle, the strut acts to press the spindle down into and retain it in axial line within the shuttle, while this position of the strut is so changed, as the bobbin-spindle is swung up, that the spring then acting against the strut, and through the strut upon the spindle-head, tends to press the spindle up, and serves to retain it in elevated position.

The spring is shown at *f*, secured to the shuttle by a screw, *g*, its front end projecting over the hinged end of the spindle, and being curved so as to form a concavity or recess, *h*, in its under surface, as seen at A.

In the top of the spindle-head, and somewhat in front of the hinge-pin *e*, is a recess or depression, *i*, and between these recesses *h i*, a strut, *k*, is placed, the strut in its normal position being inclined relatively to the spring and spindle, as seen at A. The stress of the spring exerted on the spindle-head, through this strut, thereby pressing the spring down to and holding it in its horizontal position, as shown in such view, as will be readily understood.

The upper end of the strut is immovable, (excepting vertically,) but when the spindle is swung up from the shuttle, the lower end of the strut is thereby thrown back, until, having been brought into and carried just beyond a vertical position, the change of the inclination of the strut causes it to bear upon the rear side of its bed *i*, as seen in red at A, and thereby tends to press the spindle up, and to retain it in stationary elevated position, as there shown, (the extent of its upward movement being regulated by any proper means.)

That part of the invention which relates to confining and releasing the bobbin at proper times, consists in the employment of a spring-latch plate, (a latch-tooth or detent upon which springs into a groove in the bobbin-head,) said plate being hinged to the spindle-head, and having a spiral spring, which presses the latch-tooth up into the groove in the bobbin-head, a stationary pin being so located in the shuttle, that as the spindle is thrown up, the front part of the latch-plate comes in contact with the pin, and is arrested thereby, the bobbin-groove then swinging clear of the latch, and allowing the bobbin to be freely withdrawn.

The spring-latch plate shown at *l* has an ear or projection, *m*, through which and the spindle-head, a hinge-pin, *n*, extends, the plate swinging slightly on this pin, to carry the tooth *o* on the front end of the latch-plate into and out from the groove *p*, in the periphery of the bobbin-head. Between a rear projection, *q*, from this plate, and a projection, *r*, from the spindle-head, a spiral spring, *s*, is placed; this spring tending to keep the tooth *o* pressed towards the spindle, as will readily be seen, the extent of inward movement of the tooth being fixed so as to present the inclined front surface of the tooth in such position that the bobbin-head, as it is slid

down the spindle into contact with it, will depress the tooth, which springs into the groove and confines the bobbin in place upon the spindle. When the spindle is thrown up from the shuttle, however, the inner surface of the plate *l*, just in rear of the tooth, comes in contact with a pin, *z*, which stops the plate, but allows the spindle to continue its upward movement, the tooth being thereby thrown from the bobbin-groove, (as seen in red at *A*.) enabling the empty bobbin to be slid from the spindle.

I claim, in combination with the bobbin-spindle, the spring *f* and strut *k*, arranged to operate substantially as set forth.

I also claim the hinge-latch plate *l*, the spring *s*, and the stop-pin *t*, when combined and arranged together, and relatively to the bobbin-spindle, substantially as set forth.

GEO. CROMPTON.
